United States Patent Office

Des. 193,308
Patented July 31, 1962

193,308

LAZY SUSAN OR THE LIKE

Duane O. Jackson, Waterloo, Iowa, assignor to Distinguished Gift Manufacturers, Waterloo, Iowa, a corporation of Iowa

Filed Nov. 24, 1961, Ser. No. 67,672

Term of patent 14 years

(Cl. D44—10)

FIG. 1

FIG. 2

FIG. 3

FIG. 4

FIG. 5

FIG. 1 is a perspective view of a Lazy Susan or the like showing my new design;

FIG. 2 is a side elevational view thereof with the bowls removed;

FIG. 3 is an elevational view of one of the bowls;

FIG. 4 is a top plan view thereof;

FIG. 5 is a bottom plan view thereof;

FIG. 6 is a top plan view of the article shown in FIG. 1;

FIG. 7 is a bottom plan view of the stand;

FIG. 8 is a sectional view on line 8—8 of FIG. 2; and

FIG. 9 is an elevational view of the article shown in FIG. 1.

I claim:

The ornamental design for a Lazy Susan or the like, as shown.
